PERFORATING MACHINE

Stig E. Rosenberg, Brockton, Mass.

Application February 8, 1938, Serial No. 189,370

3 Claims. (Cl. 164—93)

The present invention relates to perforating machines which are used in many industries and which have a wide use in the manufacture of shoes to ornament various forms of shoe uppers and parts thereof, and more particularly to that type of perforating machine having a perforating die and a die striking plate between which the work is impaled on the cutting edges of the die, means permitting at least one of them, the die and the plate, to yield under the impaling pressure, and rigid means mounted on the die having a striking plate impact surface arranged in the plane of said edges.

The principal objects of the present invention are to produce a perforating machine of the type hereinbefore referred to in which the yielding means is correlated with the cutting edges of the die, some of which edges are arranged in at least one cluster, to cushion the impaling pressure uniformly thereover, and to produce a perforating machine of the type hereinbefore referred to in which the rigid means, mounted on the die, having a striking plate impact surface arranged in the plane of said edges, are correlated with a work clamp having an internal window therein.

To the accomplishment of these objects, and such others as may appear hereinafter, the various features of the present invention reside in certain constructions and arrangements of parts hereinafter described and then set forth broadly and in detail in the appended claims which possess advantages readily understood by those skilled in the art.

The various features of the present invention will be understood readily from an inspection of the accompanying drawings illustrating the best forms of the invention, at present devised, in which,

Figure 1 is a detail view in front elevation showing the various features of the invention embodied in a perforating machine of the type in which the die cuts the work supported upon the striking plate;

Fig. 2 is a detail view in plan of a work supporting structure of the upstanding cutting edge die type;

Fig. 3 is a detail view in front elevation showing the various features of the present invention embodied in a perforating machine of the type in which the striking plate in moving downward impales the work upon the upstanding cutting edges of the die;

Fig. 4 is a detail view in front elevation show-

ing a modification of the features illustrated in Fig. 3, and

Fig. 5 is a diagrammatic view in plan illustrating how the rubber bed is correlated with the design of the cutting edges of the die.

In the embodiment of the invention illustrated in Fig. 1, the downwardly moving head 6 of a well-known type of perforating machine is provided with a groove 7 which receives a tongue 8 carrying a die 9 having a plurality of downwardly directed cutters or tubes 10, the cutting edges of which are arranged in a horizontal plane. As usual, in this type of die it carries a stripper plate 11 supported by the lower ends of a plurality of rods 12 which are held in a position to support the stripper plate 11 in a plane below that of the cutting edges of the die by a plurality of coiled springs 13, one for each rod. This is all standard construction in the well-known type of machine referred to.

In addition to this standard construction, the bottom of the die 9 is provided with a plurality of hardened pins 14, 15, 16 and 17, the upper ends of which are secured rigidly to the die and the lower ends of which, constituting the impact surfaces, respectively, are arranged in the plane of the cutting edges of the dies. These pins 14, 15, 16 and 17 are located outside the area occupied by the cutters or tubes 10 so that the pins clear the work during the perforating operation. Holes similar to the holes through which the cutters or tubes 10 pass are provided in the stripper plate for the free passage therethrough of the pins 14, 15, 16 and 17.

The work may be mounted on a work support 18 of the anvil type which is carried by a slide 19 to permit the anvil to be moved from a position of pressure to and from a position of clearance in a well-known manner. The portion of the work to be perforated is positioned flatwise upon a hardened steel striking plate 20 secured to the uppermost surface of the anvil. The work may be clamped to the plate 20 by a clamping mask 21 of the type illustrated in Fig. 2.

With this construction, after the work has been positioned properly on the anvil 18, the anvil 18 has been moved into the position of pressure, and the clutch of the machine thrown into operation, the head 6 is moved downwardly to cause the cutters or tubes 10 to be forced through the supported work. The stroke of the head 6 is adjusted to cause the cutting edges of the die to pass completely through the work into contact with the striking plate 20, but the force of the impact is exerted and distributed equally

over the impact surfaces of the pins 14, 15, 16 and 17, thus preventing the engagement of the striking plate and the cutting edges of the die from making any impression on either of them.

5 In order to prevent damage in the event the stroke of the head 6 is too long, a sheet of rubber 22 is interposed between the bottom of the anvil and the slide 19, the anvil 18, slide 19 and rubber sheet 22 being secured together by screws 23 threaded into the slide and loosely passing through the rubber sheet and the bottom of the anvil, a head 24 on each screw 23 serving to limit the normal position of the anvil relatively to the slide 19.

15 Referring to Fig. 3, the hardened steel striking plate 25 is mounted in the head 26 of another well-known type of perforating machine in which the head is reciprocated vertically to impale the work on the upstanding cutting edges 20 of a die 27 mounted upon the upper surface of an anvil 28 carried by a slide 29, a rubber sheet 30 being interposed between the bottom of the anvil and the slide. The die 27 is provided with the usual yieldingly mounted stripper plate 31. 25 The rigid hardened steel pins 32, 33, 34 and 35 project upward from the die 27, their impact surfaces being arranged in the plane of the cutting edges of the die. The pins 32, 33, 34 and 35 are arranged relatively to the cutting 30 edges of the die and to the work in the same manner as the pins 14, 15, 16 and 17 illustrated in Fig. 1.

As indicated in Fig. 3, the sizes of the anvil 28, slide 29 and rubber sheet 30 increase in 35 accordance with the increase in number of, or area covered by, the cutting edges of the die, in order that the impaling pressure may be transmitted uniformly over the entire surface of the sheet 22 and thus render it effective to act as 40 a yielding bed for the anvil irrespective of size thereof.

Instead of interposing the rubber sheet between the bottom of the anvil and the slide as in Figs. 1 and 2, the rubber sheet 37, (Fig. 4), 45 may be interposed between the striking plate 38 and another plate 39, the three parts being secured together in the same manner as the anvil, sheet and slide described hereinbefore. The plate 39 carries the tongue 40 which fits in the 50 groove therefore formed in the bottom of the reciprocating head 41.

As illustrated in Fig. 2 when a clamp 21 is used with the die 27, (Fig. 3), the window 42 clears the pins 33, 34, 35 and 36 which also clear the 55 work.

It will be understood by those skilled in the art that the various features of the present invention may be used just as advantageously with flat bed dies as with anvil dies. Many flat bed 60 dies are provided with a large number of cutting edges some of which are arranged in at least one cluster. Because of such an arrangement, the pressure under which the work is impaled upon the cutting edges is transmitted differen-

tially over the area defined thereby. Fig. 5 illustrates the perforations formed in a piece of work, the perforations being arranged in a line 43 and in a cluster 44. These perforations, for the purpose of disclosure, are illustrated as being superimposed upon a rubber sheet 45 of the type illustrated in Figs. 1, 3 and 4. As illustrated in Fig. 5, the rubber sheet 45 is provided with a plurality of holes 46 therein which are arranged relatively to the perforations 43 and 44 to spread the yield 10 of the rubber sheet differentially over its extent and thus correlate the yield with the differential impaling pressure exerted on the work in forming the line 43 and the cluster 44.

Nothing herein explained is to be interpreted 15 as limiting the various features of the present invention in the scope of its application to use in connection with the particular machine or the particular mode of operation or both selected for purposes of illustration and explanation. 20 While the particulars of construction herein set forth are well suited to one mechanical form of the invention and to the use to which it is put, it is not limited to this use, nor to these details of construction, nor to the conjoint use of all its 25 features, nor is it to be understood that these particulars are essential since they may be modified within the skill of the artisan without departing from the true scope of the actual invention, characterizing features of which are set 30 forth in the following claims by the intentional use of generic terms and expressions inclusive of various modifications.

What is claimed as new, is:

1. In a perforating machine, the combination 35 with a perforating die and a die striking plate between which the work is impaled on the cutting edges of the die, some of said edges being arranged in at least one cluster, of differential yielding means associated with the die correlated with the cutting edges to cushion the impaling pressure uniformly thereover.

2. In a perforating machine, the combination with a perforating die, a die striking plate between which the work is impaled on the cutting 45 edges of the die, a work supporting surface upon which the work is mounted, and a work clamp having an internal window therein, of a plurality of rigid pins, mounted on the die within the area bounded by the window, each pin having a striking plate impact surface arranged in the plane of said edges.

3. In a perforating machine, the combination with a perforating die, a die striking plate between which the work is impaled on the cutting 55 edges of the die, a work supporting surface upon which the work is mounted, and a work clamp having an internal window therein, of a plurality of rigid pins, mounted on the die within the area bounded by the window and outside the area 60 bounded by the work, each pin having a striking plate impact surface arranged in the plane of said edges.

STIG E. ROSENBERG.
